UNITED STATES PATENT OFFICE

2,008,540

AIR RECIRCULATING AND HUMIDIFYING APPARATUS

Robert U. Berry, Schenectady, N. Y., assignor to General Electric Company, a corporation of New York

Application June 29, 1934, Serial No. 733,041

6 Claims. (Cl. 261—24)

This invention relates to air conditioning and has for a principal object the provision of an improved system and apparatus for humidifying and recirculating air.

5 A more specific object of the invention is the provision of an air humidifying and circulating apparatus in the form of a self-contained unit adapted to be mounted beneath the floor of a room and to be incorporated in a ductless air recirculating system.

10 Another object of the invention is the provision of a self-contained air humidifying and circulating unit adapted to conform to and be suspended from the joist-supported floor structure of a building.

15 A further object is the provision in a building, of a ductless air recirculating system having an improved air humidifying and circulating unit whereby the rooms of the building constitute the means for conducting air to and from the unit.

20 Among the other objects of the invention which will become apparent hereinafter, is the provision in an air conditioning unit of improved means for filtering, humidifying and circulating air, and of an improved arrangement of such means whereby 25 properly conditioned air may be supplied with a maximum of efficiency and a minimum of noise and operational care.

25 A preferred embodiment of the improved air humidifying and circulating unit as illustrated and described hereinafter comprises in general an enclosing housing in the form of an inverted T, the upper or vertical leg of which is shaped to fit between the joists of the floor structure of a building, and the lower or horizontal leg of which is adapted to be suspended from the floor or joists and is provided within its interior with air filtering, humidifying and circulating means arranged in proper cooperative relationship. The 30 horizontal leg is provided with inlet openings through which air is drawn into the housing from the room or space beneath the floor, and the vertical leg is provided with an outlet opening arranged in registry with an opening in the floor 35 through which treated air is discharged into the room above the floor. Further in accordance with the present invention, the improved unit, which requires no air supply or return ducts, is incorporated in an air recirculating system 40 wherein the rooms of the building serve as means for conducting the air to and from the unit, there being provided a return opening for conveying spent air from the room or rooms above the floor, and which are to be ventilated, into the room or 45 space beneath the floor and surrounding the unit.

In the accompanying drawing Fig. 1 is a side view, partially in section, of the improved air humidifying and circulating unit and illustrates the manner of mounting the unit beneath the floor structure of the building; Fig. 2 is a plan view, partially cut away, of the unit; Fig. 3 diagrammatically illustrates the electrical control circuit for the unit and Fig. 4 diagrammatically illustrates the manner of incorporating the unit in a ductless air recirculating system for a building.

Referring particularly to Figs. 1 and 2 in which are clearly shown the details of construction of the preferred embodiment of the air humidifying and circulating unit, it will be seen that the main 15 enclosing housing 10, preferably constructed of sheet metal, is in the form of an inverted T the upper leg of which comprises a rectangular casing 11 constituting the air delivery stack of the unit and the lower or horizontal leg of which 20 comprises an elongated rectangular casing 12 having air inlet openings 13 disposed in each end thereof. 14 and 15 respectively represent the floor and supporting joists of the floor structure of a building such as that diagrammatically illustrated in Fig. 4 and in practice would be part of the floor structure separating the first floor room or rooms 16 and the basement 17 of the building 25 as shown. In the preferred embodiment of the invention the unit is designed to be hung in the 30 basement beneath the floor structure with its weight carried by hangers 18, screwed to joists 15, and mounting studs 19 which are provided on the top of the casing 12.

35 Centrally located in the top of the casing 12 is an opening 20 having an upturned rounded rim 21 around which is symmetrically disposed a rectangular upturned mounting flange 22. It is preferable that the delivery stack 11 be secured detachably to the casing 12 by means of the 40 screws 22' so that in the mounting of the unit the casing 12 may first be attached to the joists 15 as previously explained, after which the delivery stack 11 may be slipped downwardly 45 through the space between the joists 15 with its lower end fitted over the mounting flange 22 and then secured to the flange by screws 22'. The upper or discharge end of the delivery stack 11 is provided with an outwardly extending flange 23 which is adapted to be fastened over the rim 50 of the opening in the floor 14 by means of screws 24. In some installations it may be found desirable to support the whole weight of the unit from the flange 23, leaving casing 12 attached to duct 11 by screws 22', and thus eliminate the 55

necessity for hangers 18, and in other installations it may be desirable to eliminate flange 23 and to slip the delivery stack attached to the casing 12 upwardly between the joists 15 when 5 the casing is fastened to the joists. A grille 25 is placed over the opening in the floor and the discharge end of the delivery stack and may also be secured in place by means of screws 24.

One side of the casing 12 is made in the form 10 of a removable cover 26, shown partially cut away in Fig. 1, which is secured in place by means of wing nuts 27. This cover can be readily removed to give access to the interior of the unit 15 for purposes hereinafter to be pointed out. Disposed within the opening 26 in the top of the casing 12 is an annular curved wall converging mouth piece 30, held in place by means of brackets 31 which provides a round edged orifice for assuring stream lined flow of the air from the 20 casing 12 into the delivery stack 11, thereby reducing the turbulence of the air discharge and the resultant noise component of the unit.

Air filters 32 are disposed, one at each end of the casing 12 and in registry with each of the 25 inlet openings 13, as shown, and preferably consist of easily removable metal frames in which is packed steel wool, oxidized or otherwise treated to improve its efficiency as an air filtering means. It is to be understood that any other well known 30 and suitable types of removable filter frames may be used if desired. Brackets 33 are provided on the inner surfaces of the end walls of the casing 12 for supporting the filter frames.

A pair of humidifying units are also disposed 35 one within each end of the casing 12 and preferably are of the type described and illustrated in the copending application of Clarence C. Bailey, Serial No. 733,077, filed June 29, 1934, or one of the modifications thereof such as described and 40 illustrated in the copending applications of Sydney E. Miller, Serial No. 736,634, filed July 24, 1934, and M. Stanton, Serial No. 734,975, filed July 13, 1934, all of which applications are assigned to the assignee of the present invention. 45 Although the details of the humidifying units, which are illustrated in diagrammatic form only, form no portion of the present invention it may be said for purposes of completeness in this description that the preferred type of unit consists 50 in general of a plurality of horizontally disposed layers of wire mesh screen 34 capable of accumulating and suspending a multiplicity of globules of water in accordance with the principles set forth in the Bailey application referred to, and 55 stacked in superposed spaced apart relation beneath a water distributing header such as a pan 35, as shown, having openings in the bottom thereof for discharging a plurality of streams of water downwardly upon the screen stack. Preferably the openings in the pan are burred on the underneath side to prevent stoppage by scale 60 deposits as pointed out in the Bailey application. Any suitable means, such for example as that described and illustrated in the previously 65 mentioned Miller application, may be provided for supporting the screen stack beneath the water distributing header or pan 35 and it is to be understood that the supporting rods or straps 66 are shown for purposes of illustration only. Furthermore, any suitable means may be provided 70 for detachably mounting the humidifying units within the casing 12 but for purposes of illustration the mounting means are shown as 75 comprising brackets 31 depending from the top

of the casing 12 and cooperating with the flanged rims 33 of the distributing pans 35.

Air circulating means is provided within the casing 12 and in the preferred embodiment illustrated consists of a fan 40 of the Upson type disposed just beneath the discharge mouthpiece 30 and coaxial therewith, having a vertical-axis resiliently mounted driving motor 41. In the preferred embodiment of this invention the motor 41 is surrounded by a protecting housing 42 which is mounted in an opening centrally disposed in the bottom of the casing 12 and which has ventilating openings 43 disposed below the level of the casing. A pair of coiled vertical axis springs 44 are placed one at each end of and in axial alignment with the motor 41 to resiliently support the motor within the housing 42. The upper spring surrounds the motor shaft which extends beyond the housing with means on the end thereof for mounting the fan. This improved form of resilient mounting has proved to be highly effective in preventing the transmission of noise and vibration from the motor to the enclosing housing of the unit.

Water is supplied to the distributing pans 35 by 25 means of pipe 45 secured in the top of the casing 12 and having discharge nozzles 46 positioned above each of the pans. This pipe is connected at its midpoint to supply pipe 47 which in turn is connected through pipe 50, valve casing 51, pipe 52, heating coil 53, and pipe 54 to the water main (not shown). In the preferred embodiment, water for humidification is heated in the coil 53 which is disposed within a heating chamber or steam chest 55 mounted on top of the casing 12. 35 Heating medium such as steam or hot water is supplied to the heating chamber through pipe 56 from any suitable source such as the furnace 57 located in the basement of the building and which is also connected to the house heating system by 40 means of pipes 60 and 61. Pipe 62 provides means for returning heating medium from the heating chamber to the furnace and 63 represents a valve which may be employed for venting air from the heating chamber. It may be found 45 desirable in some instances to remove the heating chamber from the unit and mount it in closer proximity to the furnace, in which case the water is conveyed to the unit from the heating chamber by pipes.

The electrical control circuit for the unit comprises power line 64, transformer 65 and solenoid operated valve 66 both of which are mounted upon the unit, and hand operated switch 67 and humidistat 68 which are located at some convenient point within the building. This circuit is diagrammatically illustrated in Fig. 3 and as will be seen therefrom the fan motor 41 is connected across the power line 64 and in parallel with the primary of the transformer 65 with manually 69 operated switch 67 provided for stopping and starting the motor. Power is supplied by means of the secondary of transformer 65 to the energizing winding of solenoid operated valve 66, which winding is in series with the contacts of humidistat 68. Switch 67 controls both the fan and the power supply to the transformer and solenoid valve 66 will not open unless both the switch and the contacts of humidistat 68 are closed.

Referring again to Figs. 1 and 2, the solenoid operated valve 66 is disposed within the casing 51 for controlling the supply of humidifying water to the supply pipe 47 and distributing pipe 45. Transformer 65 is enclosed in the connection box 70 mounted on the bottom of the casing 12. 75

Power is supplied to the connection box from the supply lines 64 by means of the leads 71 and connections are made therefrom to fan motor 41 by means of cable 72, and to the solenoid operated valve by means of another cable (not shown).

In the casing 12 beneath the screen stacks 34 and surrounding the motor housing 42 is disposed a pan 73 for catching unevaporated water which drains from the screen stacks, and this pan 10 is provided with a drain pipe 74 for carrying waste water to the sewer connections as shown in Fig. 4.

In order that spent or used air may be returned from the room or rooms 16 to the basement 17 to be recirculated through the unit, a grilles opening 75 is provided in the floor 14 at a point remote from the discharge opening of the unit. Such a return opening may, however, be located in the walls or some other convenient place in a manner which will give proper communication 20 between the room 16 and the basement 17.

The operation of the improved air recirculating and humidifying system and apparatus is as follows: Fan motor 41 is started by the closing of 25 manually operated switch 67 and fan 40 operates to draw air from the basement 17 inwardly and horizontally through the openings 13, filters 32, and water evaporating screens 34 which are symmetrically disposed in opposite ends of the casing 12. The air is then forced upwardly through 30 the converging mouthpiece 30 and the delivery stack 11 and discharged through grill 25 into the room 16 through which it circulates and from which it eventually passes through grilles opening 75 back into the basement 17.

If less than the desired degree of humidity is present in the room 16, the contacts of the humidistat 68 will close thereby energizing the solenoid operated valve 66 which controls the flow of water through the casing 51. As previously described, water is supplied to the casing 51 from the water main through pipe 54, heating coil 53 in the steam chest 55, and pipe 52. The opening of the valve 66 permits the flow of water from the casing 51 through pipes 50, 47, and 45, and the nozzles 46 into the distributing pans 35. The water then flows through the holes in the bottom of the pan down onto the evaporating screens 34 where it is held momentarily in suspension in the form of drops depending from 50 the intersections of the wires of the screens as clearly pointed out in the previously referred to Bailey application, and a portion of the heated water is there evaporated by means of the current of air drawn into the casing 12 by means of the fan 40. The remainder of the water flows down into the pan 73 and from thence passes through the drain 74 to the sewer connection. Water for humidification is heated in the coil 53 by means of the steam or hot water supplied 55 through pipe 62 to the heating chamber 55 from the furnace 57 as previously pointed out.

As a precaution against wastage of water and against excess humidification upon initiation of operation of the unit the solenoid valve 66 and humidistat 68 are so connected that no water can be supplied to the evaporating unit unless switch 67 is closed and the fan motor 40 is also in operation to blow air over the evaporating unit.

The size and capacity of the various elements comprising the air humidifying and circulating unit may be varied in accordance with well known principles to meet the local conditions encountered, and the delivery stack 11 may be made of proper size to fit between the joists of the par-

ticular floor structure under which it is desired to suspend the unit. Such variations are within the range of mechanical skill and can readily be made by one skilled in the art after a proper understanding of the description herein given.

Due to the conformation and the compact and simple construction of the unit it may readily be mounted, as previously described, beneath the floor structure in any convenient place and can readily be demounted when desired. By removal 10 of the cover 26 access may be had to the interior of the unit for removal of the filtering and humidifying units for cleaning, repair and replacement. The symmetrical arrangement of the filtering and humidifying units with respect to 15 the fan, and of the fan with respect to the inlet openings in the casing 12 and the mouthpiece 30 in the delivery stack 11, results in the ability of the unit to supply the desired amount of air with a minimum amount of noise. The resilient 20 mounting of the fan motor 41 also prevents transmission of noise and vibration therefrom to the supporting structure of the unit, and the provision of the slanting fine mesh screens 79 below the screen stacks deadens the noise of the dripping of water therefrom into the pan 73.

From the above description it will be seen that I have provided a simple and compact unit particularly adapted to be suspended beneath the floor structure of a room or similar enclosure and to produce circulation of humidified air through 30 the room without the necessity for the use of air ducts. The embodiment of the invention illustrated and described herein has been selected for the purpose of clearly setting forth the principles involved and the general structural requirements. It will be apparent, however, that the invention is susceptible of being modified to meet the different conditions encountered depending upon its location and use, and I, therefore, aim to cover by the appended claims all of 40 the modifications which are within the true spirit and scope of my invention.

What I claim as new and desire to secure by Letters Patent of the United States, is:

1. An air conditioning unit comprising in combination, an enclosing casing having air inlet openings in the end walls thereof and an air exhaust opening located in the top wall thereof substantially midway between the ends thereof, one 50 of the side walls of the casing being removable to give access to the interior of the casing, a fan located in the casing substantially directly beneath said exhaust opening for drawing air in through said inlet openings and for forcing air up 55 through said exhaust opening, a motor disposed in the casing for driving the fan, a housing for totally enclosing the motor, means for resiliently mounting the motor in the housing, air filter screens removably mounted within the casing in 60 registry with each of said inlet openings, humidifying means removably mounted in each end of the casing in the path of the air drawn thereinto, means for feeding a predetermined controlled supply of humidifying water to said humidifying means and heating means mounted on the casing for controlling the temperature of the 65 humidifying water.

2. An air conditioning unit comprising an elongated enclosing casing having air inlet openings 70 in the end walls thereof and an air discharge opening in the top wall thereof, said discharge opening being located substantially midway between the ends of the casing, a vertical axis fan mounted in said casing and substantially directly 75

beneath said discharge opening for drawing air in through said inlet openings and for forcing the air out through said discharge opening, air filtering and humidifying means located in the opposite ends of the casing in the path of the air drawn thereinto, and means including a round edged orifice in said discharge opening for lessening the noise of the air discharge from the unit.

3. An air conditioning unit adapted to be suspended beneath a floor structure comprising an elongated casing having air inlet openings in the end walls thereof and an air discharge opening located in the top wall thereof substantially midway between the ends thereof, one of the side walls of the casing being removable for giving access to the interior of the casing, fan means mounted in the casing and arranged to draw air in through said inlet openings and to force the air out through said discharge opening, and a removable air filter frame and a removable humidifying unit located in each end of the casing in the path of the air drawn thereinto, said filter frame and humidifying units being slidably mounted for removal when said one side of the casing is open and means for attaching said casing beneath said floor structure.

4. An air conditioning unit adapted to be suspended beneath a floor structure, including in combination an enclosing casing having air intake openings in the end walls thereof, an air exhaust opening in the top wall thereof and an opening in the bottom wall thereof in substantially axial alignment with said exhaust opening, a substantially closed housing mounted in said last mentioned opening and extending above and below the bottom wall of said casing, an electric motor resiliently mounted in said housing with its drive shaft extending vertically through the top of said housing, said housing having openings in the walls thereof externally of said casing for admitting air to cool said motor, a fan mounted on the upper end of the motor drive shaft for drawing air in through the intake openings of said casing and for discharging the air upwardly through said exhaust opening, and air treating means mounted in said casing in the path of the indrawn air.

5. An air conditioning unit including in combination an elongated enclosing casing having air inlet openings in the end walls thereof and an air outlet opening in one of the side walls thereof substantially midway between said end walls, means providing a round-edged discharge orifice for said outlet opening, fan means located in said casing in substantially axial alignment with said outlet opening for drawing air in through said inlet opening and discharging the air outwardly through said orifice, an electric motor resiliently mounted within said casing and connected to drive said fan means, air filtering means disposed in the ends of said casing adjacent said air inlet openings, means providing humidifying zones in the ends of said casing adjacent said filtering means, means for producing a plurality of streams of water downwardly directed through said humidifying zones, a drip pan disposed in the bottom of said humidifying zones for catching un-evaporated water, and foraminous sound-deadening screens disposed over the top of said drip pan for breaking the fall of the water from said humidifying zones into said drip pan.

6. In an air conditioning unit the combination of a horizontally elongated enclosing casing having air inlet openings in the end walls thereof and an air outlet opening in the top wall thereof substantially midway between said end walls, an air outlet conduit of restricted area extending vertically upward from said outlet opening, said casing also being provided with an opening in the bottom wall thereof in substantially axial alignment with said conduit, a motor driven impeller having the driving motor thereof vertically mounted in the opening in the bottom wall of said casing with the impeller disposed in proximity to the inlet of said conduit, removable air filtering screens and water suspension screens mounted at each end of the casing and a removable water drip pan extending beneath all of said screens and provided with a central opening therein for receiving said driving motor.

ROBERT U. BERRY.
